(57) **CLAIM**

The ornamental design for a gear locking tool, as shown and described above.

DESCRIPTION

FIG. 1 is a top plan view of an ornamental design for a gear locking tool of the present invention;

FIG. 2 is a right side elevation view of an ornamental design for a gear locking tool of the present invention;

FIG. 3 is a front elevation view of an ornamental design for a gear locking tool of the present invention;

FIG. 4 is a left side elevation view of an ornamental design for a gear locking tool of the present invention;

FIG. 5 is a rear elevation view of an ornamental design for a gear locking tool of the present invention;

FIG. 6 is a bottom plan view of an ornamental design for a gear locking tool of the present invention;

FIG. 7 is a top isometric view of an ornamental design for a gear locking tool of the present invention; and,

FIG. 8 is a bottom isometric view of an ornamental design for a gear locking tool of the present invention.
